THRESHOLD CONSTRUCTION

Application filed September 29, 1930. Serial No. 485,222.

The invention relates to threshold constructions and refers more particularly to threshold constructions for swinging closures. One of the objects of the invention is to so form the threshold construction that it is adapted to be used with closures which open by swinging either inwardly or outwardly. Other objects are to so form the threshold construction that it cooperates with the closure to prevent passage therebetween of wind, water or the like; that the weatherstrip element between the threshold element and the closure is carried by the former and forms an abutment for the latter; and that the weatherstrip element is readily replaceable and does not interfere with stepping on or over the threshold construction. A further object is to so construct the threshold element that it has means for positioning the clamp which secures the weatherstrip element in place and for positioning a frame at one side of the closure.

These and other objects of the invention will become apparent from the following description taken in connection with the accompanying drawings, in which

Figure 1 is a perspective view illustrating a threshold construction embodying my invention;

Figures 2 and 3 are vertical sections therethrough;

Figures 4, 5 and 6 are views similar to Figure 2, showing modifications.

The threshold construction is designated by the reference numeral 1 and the closure by the reference numeral 2. This closure may be a door or a window and, as shown in the present instance, is a casement door of metallic construction having the side rails 3 and the bottom rail 4 of like cross section.

The threshold construction comprises the metallic threshold element 5 which is preferably formed of brass. This threshold element is of inverted channel shape and has intermediate its side legs the horizontal raised portion 6 at one edge of which are the spaced upright projections 7 extending longitudinally of the threshold element and providing spaced shoulders, which with the portion of the threshold element between the projec-

tions form the groove 8 which extends longitudinally of the threshold element and opens upwardly. At the other edge of the raised portion 6 there is the vertically extending shoulder 9 which is connected to the adjacent side leg by the inclined portion 10. The projections 7 are connected into the other side leg by the inclined portion 11, which is formed with the spaced grooves 12 extending longitudinally of the threshold element. For reinforcing the threshold element there is the longitudinally extending leg 13 located below the portion of the threshold element having the projections 7. The bottom rail 4 of the closure has the depending flange 4', which in the closed position of the closure extends adjacent the shoulder 9 of the threshold element.

14 is the weatherstrip element which, as shown in Figures 1 and 2 particularly, is formed of felt. This weatherstrip element is clamped upon the raised portion 6 of the threshold element and extends outwardly beyond the shoulder 9 to engage and form an abutment for the depending flange 4' of the closure to prevent the passage of wind, water or the like between the threshold construction and the closure. For securing the weatherstrip element in place and at the same time protecting the same, I have provided the metallic cap 15 having at one edge the leg or flange 16 which enters the groove 8 and is thereby positioned upon the threshold element. This cap rests upon and is clamped against the weatherstrip element by suitable means such as the screws 17, which are threaded into the raised portion 6.

With this arrangement the weatherstrip element is protected and does not interfere with stepping on or over the threshold construction. Also it forms an effective seal between the closure and the threshold construction and a yieldable abutment for the closure to eliminate at least in part jar and noise incident to moving the closure to closed position.

As shown particularly in Figures 1 and 3, a window frame is located at one side of the casement door frame 18 and secured to the threshold element 5. This window frame is of metallic construction and has side and bot-

tom rails 19 and 20, respectively, of like cross section. This window frame is positioned upon the threshold element by engagement of the leg 21 of the bottom rail in the groove 8 of the threshold element, the other leg 22 overlapping the shoulder 9. The window frame is secured to the threshold element by suitable means such as the screws 23. It will thus be seen that the groove 8, in addition to positioning the cap for clamping the weatherstrip element in place, positions the window frame and that the reinforcing leg of the threshold element serves to reinforce the same and to carry the load of the window, as well as that incident to stepping upon the threshold construction.

In the modification shown in Figure 4, the casement closure opens inwardly instead of outwardly, as shown in Figures 1, 2 and 3, and the threshold construction is reversed to adapt the same to this type of closure. This closure is also a casement door of metallic construction and is glazed on the outside and to assist in weatherproofing, there is the metallic weatherstrip element 24 which is secured upon the bottom rail of the door outside the glass and has the downwardly and outwardly inclined flange 25 terminating a substantial distance outwardly from the space between the bottom rail and the threshold construction.

In the modification shown in Figure 5, the same general arrangement of parts is present, with the exception that the weatherstrip element 26 is clamped in place by an integral part 27 of the threshold element. This weatherstrip element is inserted into place when the part 27 occupies the position shown by the dotted lines and after having been inserted into place the part 27 is pressed down to tightly engage the weatherstrip element.

Figure 6 discloses another modification in which the weatherstrip element 28 is formed of spring metal, such as spring bronze, and it is secured in place by means of the cap 29, which in turn is secured to the raised portion of the threshold element by means of the screws 30.

50. What I claim as my invention is:

1. A threshold construction for a swinging closure provided with a depending flange, which comprises a threshold element having a shoulder adjacent which the depending flange extends in the closed position of the closure, and a weatherstrip element secured to said threshold element and extending beyond said shoulder and forming an abutment for the depending flange.

60. 2. A threshold construction for a closure, which comprises a threshold element having a shoulder extending longitudinally thereof for positioning a frame adjacent the closure when closed, a cap positioned by said shoulder and secured to said threshold element,

and a weatherstrip element engageable with the closure and clamped to said threshold element by said cap.

3. A threshold construction for a swinging closure, which comprises a threshold element having a longitudinally extending upwardly opening groove for receiving and positioning a frame secured to said threshold element adjacent the closure, a cap positioned by said upwardly opening groove and secured to said threshold element, and a weatherstrip element engageable with the closure and clamped to said threshold element by said cap.

4. A threshold construction for a swinging closure, which comprises a threshold element having a shoulder, a weatherstrip element forming an abutment for the closure, and a cap positioned by said shoulder and secured to said threshold element and clamping said weatherstrip element to said threshold element.

5. A threshold construction for a closure, which comprises a threshold element having a longitudinally extending upwardly opening groove, a weatherstrip element extending longitudinally of said threshold element at one side of said groove, and a cap engaging said groove and secured to said threshold element and clamping said weatherstrip element to said threshold element.

6. A threshold construction, which comprises a threshold element of inverted channel shape having a longitudinally extending upwardly opening groove intermediate its legs for receiving and positioning a member, and a longitudinally extending reinforcing leg integral with said threshold element and located below said groove.

7. A threshold construction for a closure, which comprises a threshold element having a shoulder extending longitudinally thereof for positioning a frame, a weatherstrip element engageable with the closure, and means positioned by said shoulder for securing said weatherstrip element in place.

In testimony whereof I affix my signature.

CLYDE W. KELLY.
